UNITED STATES PATENT OFFICE.

WALTER WRIGHT, OF NEW YORK, N. Y., ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,251,726.

Specification of Letters Patent.

Patented Jan. 1, 1918.

Application filed December 24, 1910, Serial No. 599,184. Renewed August 19, 1912. Serial No. 715,916.

To all whom it may concern:

Be it known that I, WALTER WRIGHT, a citizen of the United States, residing in New York, in the county of New York and State of New York, have invented certain new and useful Improvements in Combined Type-Writing and Computing Machines, of which the following is a specification.

This invention relates to computing machines of the class shown in the pending application No. 543,603, of Wright and Degener, filed February 12, 1910, in which a constantly revolving power shaft is caused to assist at the operation of carrying tens 15 from one computing wheel to the next.

One of the objects of the present invention is to improve the means for connecting the computing wheels temporarily with the power shaft at the tens-carrying operation, especially with a view to making the device 20 more durable, and to producing an efficient and simple mechanism at low cost.

In said application, the tens-carrying devices include a normally stationary three-part rotary device, one part consisting of a five-toothed wheel which is struck intermittently by a special tooth on the computing wheel; another part consisting of a pinion in mesh with the computing wheel of next 30 higher denomination, the diameter of this pinion being half that of the computing wheel, and the third part consisting of a five-lobed wheel, which, at the beginning of the tens-carrying operation, turns into engagement with a constantly-revolving shaft or member, whereby power is temporarily imparted to said three-wheel rotary device, to assist it in completing the tens-carrying operation.

According to the present improvements, a rolling device (preferably a pinion) is employed to transmit movement from the constantly rotating member to the five-lobed wheel aforesaid, said pinion being caused to mesh with teeth formed upon the ends of the lobes of said lobed wheel, and also to mesh with the constantly revolving member, which is preferably in the form of a pinion, whereby a powerful impetus is given to the tens-carrying members, and durability of the machine is increased.

Other features and advantages will hereinafter appear.

In the accompanying drawings.

Figure 1 is a side elevation of an Under-

wood combined typewriting and computing machine provided with the present improvements.

Fig. 2 is a sectional side elevation on a larger scale, taken through the computing mechanism.

Fig. 3 is a part sectional rear elevation of the computing head.

Fig. 4 is a sectional side elevation similar to a part of Fig. 2, but illustrating the tens-carrying operation.

Fig. 5 is a rear perspective of a portion of the computing train.

Fig. 6 is a sectional detail of the tens-carrying mechanism.

A constantly revolving electric motor 1 is connected by a friction clutch 2, pinions 3 and 4, shaft 5, bevel pinions 6 and 7 and gears 8, 9, to a primary escapement wheel 10, under constant tension counterclockwise 75 at Fig. 1, and having a series of pins 11, the latter settable by the numeral keys 12 of the typewriter 13; said keys also having means to reciprocate a pair of dogs 14, 15, which control the movements of a secondary escapement wheel 16, to which is fixed a pinion 17, adapted to be driven intermittently by such pins 11 as are projected by the finger keys.

Meshing with the bevel pinion 7 is a bevel pinion 18 on a shaft 19, upon which is also fixed a pinion 20, the latter meshing with a pinion 21 on a vertical shaft 22. This shaft 22 carries at its upper end a pinion 23, meshing with a pinion 24 upon a horizontal shaft 90 25, to which is fixed a master wheel 26, having opposite teeth 27 to engage interior notches 28 in a gang of computing wheels 29; said gang mounted on a carriage 30, which travels on rails 31, 32, and is connected by an arm 33 to the carriage 34 of the typewriting machine; said carriage 34 having a platen 35, against the front of which strike types 36; and said carriage also having a rack 37 meshing with a pinion 38 100 connected to an escapement wheel 39, which is controlled by key-operated dogs 40, 41.

The computing wheels 29 mesh with gears 30 provided upon number-bearing wheels 31. All of the foregoing parts are set forth in said pending application, and form no part of the present invention.

Each computing wheel 29 is provided with a tens-carrying tooth 42, which, once in each revolution of said wheel, strikes one of the 110

five teeth 43 of a revoluble wheel 44, thereby starting or performing a portion of the tens-carrying operation.

On this wheel 44 is fixed a pinion 45, which meshes with the computing wheel 29 of next higher denomination, so that when said five-toothed wheel 44 is rotated one-fifth of a revolution, the next higher computing wheel is rotated one-tenth of a revolution, thus adding one on the higher wheel.

The present invention relates to the auxiliary tens-carrying mechanism, that is, the means whereby the tens-carrying operation is assisted or largely performed. This mechanism includes a five-lobed wheel, that may be located between the wheel 44 and pinion 45, and fixed to both thereof. Between the lobes 46 of this middle wheel are formed depressions or notches 47, engageable by a yielding detent 48, in the form of a roll or wheel provided upon the end of an arm 49, and pressed by a spring 50 into the notch 47.

The detent 48 is provided upon its periphery with fine teeth or serrations, which perform a special function at the tens-carrying operation, without detracting from the usefulness of the wheel as a detent. During that portion of the revolution of the five-lobed wheel 46, which is effected by the tens-carrying tooth 42, the serrations or teeth 51 formed upon the adjoining lobe 46 come into mesh with the serrations on the detent 48; the latter yielding at the rotation of the lobed-wheel 46, and riding upon the end of said lobe, as will be understood by reference to Fig. 4. This backward yielding movement of the wheel 48 not only brings it into mesh with said teeth 51, but also brings said wheel 48 into mesh with a pinion 52 fixed on a constantly revolving shaft 52*, which thus serves as an auxiliary driver for assisting or completing the tens-carrying operation. This pinion 52 (of which there is one for each lobed wheel 46) is moving at high speed in the same rotary direction as the lobed-wheel 46, and the wheel 48, upon meshing with 52, therefore serves to transmit movement from 52 to 46, thereby completing the motion of the lobed-wheel 46, as well as of the pinion 45; while the wheel 48 snaps bodily into the next recess or notch 47 in the lobed wheel, thereby not only becoming disconnected from the barrel pinion 52, but also properly positioning the wheel 46, etc., and the computing wheel 29 of next higher denomination.

The assisting shaft 52* is kept in constant rotation by means of the electric motor 1; the connection including a pinion 53 on the shaft of the motor, a pinion 54 in mesh therewith, a pinion 55, bevel pinions 56 and 57, shaft 58, bevel pinions 59, 60, shaft 61, bevel pinions 62, 63, shaft 64, pinions 65, 66,

shaft 67, and pinion 67* thereon meshing with pinion 52* on shaft 52*.

It will be seen that so long as the interponent 48 can be moved by the lobes 46 into contact with the constantly revolving driver 52, so as to serve as a movement-transmitter between 52 and 46, it is not essential in all cases that the teeth or serrations be provided upon all or any of these members, since the member 52 might be in the form of a smooth soft rubber cylinder, as illustrated in certain of my other pending applications; and other variations may be resorted to within the scope of this portion of the invention.

In the presence instance, the carriage 30* contains all of the computing wheels 29 and the number wheels 30, and carries them bodily step-by-step to accompany the movements of the carriage of the typewriter, 85 while the master wheel 26 does not travel; and it results that the computing wheels 29 are presented successively to the master wheel, to be operated thereby.

Upon the constantly revolving shaft 64 is fixed a pinion 65, meshing with a pinion 66, the latter splined or fitted upon a square shaft 67, which is movable endwise with the computing carriage 30*; said shaft having at its ends bosses 68 journaled by ball bearings in arm 69 of said carriage 30*. The pinion 66 has a hub 70, journaled by ball bearings in a portion 71 of the general framework of the machine.

Variations may be resorted to within the scope of the invention, and portions of the improvements may be used without others.

Having thus described my invention, I claim:

1. In a computing device, the combination with a set of computing wheels, of tens-carrying mechanism comprising a rotary member connected to a wheel of high denomination and having a part intermittently operable by a wheel of low denomination, said rotary member including a lobed wheel, a roll normally occupying a depression in said lobed wheel and constructed to ride upon the periphery of a lobe at the tens-carrying operation, and a constantly revolving driver with which said roll engages and by which it is driven when riding upon said periphery, whereby said driver is caused to assist said rotary member.

2. In a computing device, the combination with a set of computing wheels, of tens-carrying mechanism comprising a rotary member connected to a wheel of high denomination and having a part intermittently operable by a wheel of low denomination, said rotary member including a lobed wheel, a roll normally occupying a depression in said lobed wheel, yielding means holding said roll in the depression and permitting the roll to yield to said lobed wheel when the

latter turns, and a constantly revolving driver into engagement with which said roll is pressed by said lobed wheel, to enable said driver to impart movement through said rotary member to the computing wheel of high denomination.

3. In combination, a pinion, a constantly revolving driver, and a lobed carry-over wheel having teeth on the periphery of its lobes for engagement with the pinion when the latter is moved into mesh with the constantly revolving driver.

4. In a computing device, the combination with a set of computing wheels and a constantly revolving gear, of normally silenced gear trains between said computing wheels and said revolving gear, and means to enable the computing wheels to call said gear trains into action and cause them to aid in carrying tens, each train comprising a toothed wheel and a transmitter out of mesh therewith, and means for moving said transmitter into mesh with said toothed wheel.

5. In a computing device, the combination with a set of computing wheels and a constantly revolving gear, of normally idle gear trains between said computing wheels and said revolving driver, and means to enable the computing wheels to call said gear trains into action and cause them to aid in carrying tens from one computing wheel to the next; each train comprising a toothed wheel and a transmitter out of mesh therewith; means being provided for moving said transmitter into mesh with both said toothed wheel and said constantly revolving gear.

6. In a computing device, the combination with a set of computing wheels and a constantly rotating driver, of normally idle tens-carrying mechanisms between the computing wheels and the driver and each including a transmitter movable simultaneously into engagement with both the driver and certain of the tens-carrying members, for enabling the driver to assist at the tens-carrying operation.

7. In a tens-carrying train, a carry-over wheel divided into lobes, and having teeth on the tips of the lobes, said tips corresponding to the periphery of the wheel, a detent wheel adapted to rest between said lobes, and means for driving said lobed wheel by said detent wheel, substantially as and for the purpose set forth.

8. In a typewriting and computing machine, the combination with a computing wheel and a tens-carrying train, of a roll used alternately to detain and drive the tens-carrying train, and means independent of said wheel for so driving said train.

9. In a typewriting and computing machine, the combination with a tens-carrying train, of a roll used alternately to detain and drive the tens-carrying train, and means normally out of connection with the roll to

cause the same to drive said tens-carrying train.

10. In a typewriting and computing machine, the combination with a tens-carrying train, of a roll used alternately to detain and drive the tens-carrying train, means normally out of connection with the roll to cause the same to drive said tens-carrying train, and means for moving said roll out of normal position into position to be driven by said means to drive said train.

11. A computing device having computing wheels initiating a tens carrying operation, a lobed wheel forming part of a tens carrying train and adapted to be moved at initiation of said operation, a detent for said lobed wheel, and an individual assisting gear for each computing wheel to drive said computing wheel by its detent to complete the tens carrying operation.

12. In a computing device, the combination with a set of computing wheels, a device for transferring a partial rotation from each wheel to the next higher wheel to carry tens, a gear individual to each of said devices, a normally ineffective gear to form an intermediary between said gear and said device, whereby the former can drive the latter to assist in tens carrying, and a special tooth on each of said wheels co-operating with said device to determine when said normally ineffective gear shall be brought into action as a gear.

13. The combination with a plurality of computing wheels, of intermediate wheels for carrying tens between wheels of next adjacent denominations, means carried by each computing wheel to enable the initiation of a tens-carrying action, a detent on which said means is effective, a toothed wheel forming part of each detent, and a completely toothed assisting gear effective to turn said detent wheel to drive said intermediate wheels at any point in the entire periphery of the assisting gear, so as to enable the carrying of tens at the instant of a tens-carrying operation initiated by a computing wheel.

14. The combination with a series of computing wheels, of a tens-carrying train between adjacent computing wheels, each computing wheel having means to initiate a tens-carrying operation, a detent on which the tens-carrying train is effective, a toothed wheel forming part of each detent and continuously driven assisting gears individual to each computing wheel to drive the detent wheel for completing the tens-carrying operation.

15. The combination with a series of computing wheels, of a tens-carrying gear connecting adjacent computing wheels, a driving gear, means independent of the computing wheels for driving said driving gear, and an intermediate floating gear acting

- sometimes as a holding means for said tens-carrying gear and sometimes as a driver for said tens-carrying gear, moving between holding and driving positions.
- 5 16. The combination with a series of computing wheels, of tens-carrying connections between adjacent computing wheels, holding means for each computing wheel, means for concomitantly initiating the tens-carrying operation and releasing said holding means, a source of power independent of the computing wheels, and means for completing the tens carrying operation by said source of power.
- 10 17. In a computing machine, the combination with a power-driven master wheel, of tens-carrying devices comprising spring detents, and power-driven means rotating independently of the said master wheel for moving said detents to effect tens-carrying thereby.
- 15 18. In a computing machine, the combination with computing wheels, of a computing escapement, a master wheel to turn said computing wheels as determined by said escapement, a power shaft adapted to rotate independently of said master wheel, carry-over devices for said computing wheels, spring detents forming part of said carry-over devices, and means for driving said computing wheels by said detents from said independent power shaft.
- 20 19. In a computing machine, the combination with computing wheels, of a computing escapement, a master wheel to turn said computing wheels as determined by said escapement, a power shaft adapted to rotate independently of said master wheel, carry-over devices for said computing wheels, lobed toothed wheels forming part of said
- 25 30
- 35 40
- 45 50
- 55 60
- 65 70
- 75
- ing with said lobes to hold said computing wheels, toothed wheels forming part of said detents, and means for driving said lobed wheels by said detents from said independent power shaft.
20. In a computing machine, the combination with computing wheels, and a computing escapement for said wheels, of detents for said computing wheels, lobes for centering said wheels by said detents, toothed wheels forming part of said detents, means for driving said computing wheels by said detents, and teeth on the ends of said lobes coöperating with said toothed wheels and forming part of said driving means.
21. In a computing machine, the combination with computing wheels, and a computing escapement, of detents for said computing wheels, toothed wheels forming part of said detents, lobed wheels constantly in gear with said computing wheels, said detents effective on said lobed wheels, teeth on said lobed wheels, and means for driving said lobed wheels by said detent wheels through their respective teeth.
22. In a computing machine, the combination with a series of computing wheels, and a master wheel, of a computing escapement for controlling said master wheel, toothed detents for holding said computing wheels, and means independent of the master wheel and computing wheels for driving said computing wheels by the teeth on said detents to effect a carry-over onto one computing wheel from the one below.

WALTER WRIGHT.
